UNITED STATES PATENT OFFICE.

DAVID M. MILLER, OF SOUTH BEND, INDIANA.

IMPROVEMENT IN CAR-COUPINGS.

Specification forming part of Letters Patent No. **143,368**, dated September 30, 1873; application filed August 28, 1873.

To all whom it may concern:

Be it known that I, DAVID M. MILLER, of South Bend, in the county of St. Joseph and State of Indiana, have invented a certain Improvement in Car-Couplings, of which the following is a specification:

This invention relates to that class of car-couplings in which the pin automatically engages an entering link. My improvement consists in the employment, with a coupling-pin supported upon the free end of a plate-spring underneath the draw-head, and fastened thereto, of a lever which, when turned into a vertical, or nearly vertical, position by means of the transverse rock-shaft or rod to which it is attached, will depress the spring, and thereby draw the coupling-pin out of the cavity of the draw-head, and a suitable projection on the draw-head or its shank, which, when the latter is pushed inward by an approaching car, turns the locking or retaining lever sufficiently to release the spring, by the recoil of which the pin is then passed through the draw-head to lock the link just entered.

In the annexed drawings, Figure 1 is a sectional elevation of a draw-head with my improvements attached, showing the spring bent down by the lever and the coupling-pin withdrawn. Fig. 2 is a sectional elevation of two adjacent draw-heads coupled together. Fig. 3 is a bottom view of the end of a car, the draw-head of which is provided with my improvements.

The same letters of reference are used in all the figures in the designation of identical parts.

The draw-heads illustrated are of the kind now in most general use, their shanks bearing against suitable buffer-springs in the usual well-known manner.

The pin B is operated from underneath the draw-head A, it being secured to the free end of a spring, C, which is in turn made fast at its other end to the draw-head or its shank, as clearly shown. An india-rubber cushion, b, placed around the coupling-pin between a collar, b', thereon and the spring C, provides for the necessary oscillation of the pin as it is drawn outward by the spring, and also causes it

to assume its erect position in passing through the draw-head. The pin is placed in a slightly-elongated hole in the spring C, permitting the rocking of the pin spoken of, and secured by a key or nuts. D refers to a transverse rod or rock-shaft, having its bearings in hangers attached to the side sills of the car-body. It passes between the draw-head A and the spring C, and, extending to the sides of the car, is provided with crank-arms d and d', by means of which it may be readily turned. A lever, E, is firmly secured to this rod directly underneath the draw-head. When turned into an erect position, as shown in Fig. 1, its long arm e will have depressed the free end of the spring C so far as to draw the pin out of the way of an entering coupling-link, F, and its short arm e' will bear against a projection, a, on the draw-head. To properly lock the spring in this position, the lever E must be turned into a slightly-inclined position, as shown. A stop, c, may also be attached to the spring to prevent the lever being turned back too far. As the draw-head is pushed inward by an approaching car its projection a turns the lever far enough to unlock the spring from the arm e thereof, and the spring immediately recoils and passes the pin through the draw-head, as shown in Fig. 2.

What I claim as my invention, and desire to secure by Letters Patent, is—

1. The combination of the draw-head A, having a projection, a, pin B, spring C, and lever or prop E, substantially as and for the purpose specified.

2. The combination of the draw-head A a, pin B, spring C, lever or prop E, and rock-shaft or rod D, extending to the sides of the car, substantially as and for the purpose specified.

3. The combination of the pin B, spring C, and rubber or other spring b, substantially as and for the purpose specified.

In testimony whereof I have signed my name to this specification in the presence of two subscribing witnesses.

Witnesses: DAVID M. MILLER.
